CLAIM

I claim the ornamental design for a mounting hook, as shown and described.

DESCRIPTION

FIG. 1 is a front left perspective view of a first embodiment of a mounting hook, according to my design;
FIG. 2 is a front view of the mounting hook of FIG. 1;
FIG. 3 is a rear view of the mounting hook of FIG. 1;
FIG. 4 is a left side view of the mounting hook of FIG. 1;
FIG. 5 is a right side view of the mounting hook of FIG. 1;
FIG. 6 is a top view of the mounting hook of FIG. 1;
FIG. 7 is a bottom view of the mounting hook of FIG. 1;
FIG. 8 is a front left perspective view of a second embodiment of a mounting hook, according to my design;
FIG. 9 is a front view of the mounting hook of FIG. 8;
FIG. 10 is a rear view of the mounting hook of FIG. 8;
FIG. 11 is a left side view of the mounting hook of FIG. 8;
FIG. 12 is a right side view of the mounting hook of FIG. 8;
FIG. 13 is a top view of the mounting hook of FIG. 8; and,
FIG. 14 is a bottom view of the mounting hook of FIG. 8.
The broken lines shown in the drawings illustrate portions of the mounting hook that form no part of the claimed design.

1 Claim, 13 Drawing Sheets
